FIG. 6.

FIG. 2.

FIG. 5.

UNITED STATES PATENT OFFICE.

JOHN O'CALLAHAN, OF CHICAGO, ILLINOIS.

CURTAIN-FRAME.

1,335,854.

Specification of Letters Patent.

Patented Apr. 6, 1920.

Application filed August 16, 1919. Serial No. 317,983.

To all whom it may concern:

Be it known that I, JOHN O'CALLAHAN, a citizen of the United States, residing at Chicago, in the county of Cook and State of Illinois, have invented new and useful Improvements in Curtain-Frames, of which the following is a specification.

The frame which is the subject matter of the present application for patent has been designed more particularly for holding curtains of that kind which are stretched over glass-paneled doors, and the invention has for its object to provide a frame which can be readily adjusted as to size, and which permits the curtain to be readily applied thereto or removed.

The object stated is attained by means of a novel combination and arrangement of parts to be hereinafter described and claimed, and in order that the same may be better understood, reference is had to the accompanying drawing forming a part of this specification.

In the drawing,

25 Fig. 1 is an elevation of the invention; Fig. 2 is a perspective view of a fragment of the curtain;

Fig. 3 is a cross section showing a supporting means;

30 Fig. 4 is a section on the line 4—4 of Fig. 1;

Fig. 5 is a detail in perspective, and

Fig. 6 is a rear elevation, showing one corner of the frame.

35 In carrying out the invention there is provided a rectangular frame composed of tubular side, top and bottom members held in assembled relation by angular corner pieces 10. Each of the side members is composed of two telescopically connected sections 11 and 12, respectively, so that it may be lengthened or shortened, and for the same purpose, the top is composed of two similarly connected sections 13 and 14, and the bottom is composed of similarly connected sections 15 and 16. The frame can therefore be extended or contracted in the direction of its height and width, and thus set

for curtains of various sizes. The corner pieces 10 are also tubular and the frame members are telescopically connected thereto.

50 In preparing the curtain 17 for the frame, rigid wire rods 18 are passed into edge hemps of the curtain, the ends of the rods being forked, as shown at 19 for hooking to the 55 corners of the curtain to prevent the latter from collapsing and to hold it tightly stretched. All the members of the frame are slitted on the inside, as shown at 20. The rods 18 are adapted to be seated in the 60 frame members, they being tubular as hereinbefore described, with the curtain 17 issuing from the slits 20.

To apply the curtain 17 to the frame, the members thereof are separated at the 65 corners, and the edges of the curtain, with the rods 18, are inserted into the respective members. The corner pieces 10 are then applied to hold the frame members assembled, after which the parts are expanded to draw 70 the curtain taut. The frame sections are made with interlocking indentations 21 to prevent relative twisting thereof which would bring the slits 20 out of alinement.

75 The frame may be suspended on the door or other part by hooks 22 which enter slots 23 in the back of the top frame sections 13 and 14. Any other expedient may be resorted to for supporting the frame.

I claim:

80 A curtain frame composed of tubular side, top and bottom members, and rigid tubular corner members holding the same assembled, each of said side, top and bottom members being composed of telescopically 85 connected sections, said frame members being slitted longitudinally on the inside of the frame, and the side, top and bottom members being telescopically connected to the corner members; in combination with a 90 curtain having rigid rods attached to its edges, said edge portions and the rods being adapted to seat in the frame members, with the curtain issuing from the slits thereof.

95 In testimony whereof I affix my signature.

JOHN O'CALLAHAN.
